(57) **CLAIM**

The ornamental design of a travel kit, as shown and described.

DESCRIPTION

FIG. 1 is a perspective view of the travel kit showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is an exploded rear elevational view thereof showing the travel kit design with contents.

The broken lines shown in the drawings are included for purpose of illustrating environmental structure and form no part of the claimed design.
